UNITED STATES PATENT OFFICE.

EDWARD E. STEVENSON, OF LOS ANGELES, CALIFORNIA, ASSIGNOR, BY MESNE ASSIGNMENTS, TO EMSCO DERRICK & EQUIPMENT COMPANY, OF LOS ANGELES, CALIFORNIA, A CORPORATION OF CALIFORNIA.

SUCKER-ROD ELEVATOR.

Application filed February 8, 1926. Serial No. 86,690.

This invention relates to devices for suspending, raising and lowering sucker rods used in connection with the operation of deep well pumps.

5 It is the general object of the invention to provide an elevator which is highly efficient in operation, that is, one which may be applied to and removed from the rods with minimum effort and loss of time and yet insure that the rods be positively held against release except by willful effort on the part of the operator.

10 The elevator is made up of very few moving parts and consequently may be manufactured at comparatively little cost, and such parts as make it up are of very sturdy construction to enable the device to stand up well under the severe service conditions to which elevators of this type are exposed. The 15 extreme simplicity of the device and its operation adds appreciably to its value as a tool used by the comparatively unskilled worker in the field, and its sureness of hold is an exceedingly valuable feature, since an elevator's failure to hold may often result in tremendous loss to the well operator due to the 20 labor and expense of fishing for the "lost" string as well as the economic losses arising from the non-productiveness of the well during 25 the time consumed in fishing.

The elevator may be applied to the rod merely by thrusting it laterally thereonto, the jaws being spring-pressed into a position to secure the rod in the elevator way as soon 30 as said rod is fully taken thereby. Due to the peculiar method of mounting the jaws, they cannot thereafter be forced open except by willful manipulation by the operator. That is, if such lateral pressure be exerted 35 against the elevator or rod as would tend to move the rod out of the way, the jaws resist and finally prevent such movement. However, when the operator is ready to release the elevator, he need only grasp the two-part 40 operating handle, squeeze the two parts together, thereby moving the jaws to release position, and by simultaneously drawing the elevator towards him with the squeezing hand, the elevator is freed from the rod. The 45 operator can perform these two operations without conscious thought that he is doing more than merely pulling the elevator free, for it is natural to take a tight, squeezing grip 50 on any tool of this character before starting

to draw it from the work. If a pull be exerted on only one part of the handle, the jaws will not move to release position, thus eliminating the chance of some extraneous object, such as a cable or swinging tool, from contacting with either part of the handle with sufficient force to cause jaw opening movement. But it is to be noted particularly that I do not employ a separate latching member for holding the jaws against such accidental release, but may rely entirely upon the disposition and 55 nature of the jaws. The advantages of this feature from the standpoints of economical manufacture, simplicity, ease and quickness of operation, and cost of upkeep, are self-evident.

60 The above features, as well as others, will be explained in the following detailed description, reference being had to the accompanying drawings, in which:

65 Fig. 1 is a front elevation of an elevator embodying my invention;

70 Fig. 2 is a plan view of Fig. 1, showing the bail eyes in section, and showing a rod secured within the elevator;

75 Fig. 3 is a section on line 3—3 of Fig. 1 except that the jaws are shown in full plan;

80 Fig. 4 is a perspective view of one of the jaws;

85 Fig. 5 is a view similar to Fig. 3 but showing the position of the parts when the elevator is being applied to or withdrawn from a rod;

90 Fig. 6 is a view similar to Fig. 3 but showing the rod moved into contact with the inner faces of the jaw noses;

95 Fig. 7 is a section on line 7—7 of Fig. 1; and

Fig. 8 shows a variational form wherein only a single jaw is used.

100 In the drawings, numeral 10 indicates the body portion or member of the elevator, this member being cored out centrally to provide a chamber 11 for the reception of the jaw mechanism. Extending from one side of member 10 are the arms 12 which support a relatively stationary hand grip or cross bar 13 forming one of the parts of the two-part jaw operating handle. Chamber 11 opens at one side 14 towards grip 13, while, at the front of the body member, plate portions 15 and 16, which define the top and bottom of chamber 11, respectively, are cut to form vertically alined, and horizontally elongated

rod receiving ways 17, the mouths of which are preferably flare as at 18, for obvious reasons, and the rear walls of which are indicated at 19 (Fig. 5). Hereafter, the ways in the two plates will, together, be referred to as comprising the rod receiving way of the elevator. The plates 15 and 16 are preferably slightly countersunk at 17^a to receive the tapered shoulder (not shown) usually provided at the 10 joints of sucker rods.

Trunnions 20 extend from opposite sides of member 10, their common axis intersecting the vertical axial plane of way 17 approximately at the point where the axis of rod 15 R will lie when the rod is secured in the elevator. Trunnions 20 have annular grooves 21 adapted to receive the eyes 22 of bail 23, body member 10 thus being mounted for oscillatory movement with respect to the bail, 20 the reason for providing this type of mounting being well understood by those skilled in the art. The ends 20^a are, in effect, flanged end portions of the trunnions, and being of larger diameter than the inside diameter of 25 the bail eyes, hold said eyes from separative displacement from the elevator body.

Jaws 24 are made up of reversely curved body portions 25 which cross or overlap one another approximately at their centers, and 30 way closing noses 26 having inclined, outer cam faces 27 and inner, rod engaging faces 28. In order that the noses of the two jaws may be in horizontal opposition, they are built up from the body portions of their respective jaws, as at 28^a, the jaws being so 35 relatively arranged that portion 28^a on the lower jaw extends upwardly and portion 28^a on the upper jaw extends downwardly.

The jaws lie within chamber 11 and are 40 pivotally connected at 29 to member 10 so they can be pivotally moved to project across way 17 to secure rod R therein (Figs. 2, 3 and 6) and pivotally moved to a release position entirely within chamber 11, (Fig. 5) thus 45 clearing way 17 for the passage in or out of rod R. The jaws may thus be considered as being oscillatory members adapted to be oscillated to and from way-closing or rod-seizing position. While the jaws may be 50 pivotally connected to the body member in any suitable way, I prefer to provide the type of connection illustrated, which may be described as a gear tooth connection, there being a pin 30 pivotally connecting the jaws 55 intermediate their ends to hold arcuate or tooth ends 31 of jaws 24 loosely in the sockets 32 which are formed in body 10 between spaced lugs or internal teeth 33. This loose type of pivotal connection between jaws and 60 body is advantageous in that it requires no machining, separable parts, nor tools for assembly, and give sufficient lateral play to the jaws to allow the lost motion requisite to the pivotal movement thereof, though such 65 lost motion may occur between the jaws and

pivot pin, if such an arrangement is preferred.

Pin 30 is supported by the fork arms 34 at the end of leg or shank 35 of relatively movable hand grip 36 which is of T-shape and is the second part of the two-part jaw operating handle. Cross bar 37 of grip 36 is preferably of channel cross-section and approximately parallels bar 13. Arms 12 and side flanges 38 on bar 13 hold grip 37 from 75 becoming inoperatively displaced.

Shank 35 has a central bore 39 adapted to take a slideable plunger 40. Bore 41 is provided in bar 13, this bore being in line with bore 39 so the plunger, which has a head 42, may be thrust into said bore 39, a retention plug 43 being threaded into bore 41 after plunger 40 is thrust to position. An expansive spring 44 encircles plunger 40 between head 42 and the shoulder 45 formed in bar 37 85 by countersinking it at 46, and the spring tends yieldingly to spread bar 37 apart from bar 13. Thus, the spring acts through shank 35, arms 34 and pin 30, against jaws 24 to swing them pivotally downwardly in a manner to project noses 26 across way 17 and preferably into contact with each other, or in other words, to hold the jaws yieldingly in rod-seizing or way-closing position.

To explain the peculiar nature and mounting of the jaws, it will be well to consider the rod R as being fully inserted in the elevator and the jaws as being closed. For the time being I will refer to Fig. 6. Noses 26 project across way 17 at such a point that rod R, of less than a given prohibitive diameter, is capable of limited movement laterally with respect to the body member in the direction of the long dimension of way 17. The jaws and noses are so shaped that when the rod or body is moved laterally to bring the rod and nose faces 28 into engagement, there will be points of engagement which lie at that side of the common axial plane A of a given pivot point 29 and rod R which is remote from the body portion of the corresponding jaw, and the noses are so shaped and proportioned that the distance B between the given pivot point and point of nose engagement with the rod is less than the distance between said pivot point 110 and the far side C of the rod, as measured on said common axial plane A. Consequently, with the rod in place, when body member 10 is thrust in the direction of arrow D, or a thrust is exerted against the inclined faces 27 of noses 26 in the direction of arrow D, or a mere pull is exerted on grip 36 (that is, when bars 13 and 37 are not squeezed together) as may occur when an extraneous body is accidentally thrust against the jaws or body member or is hooked over bar 37, jaws 24 cannot be moved pivotally by the exertion of such simple forces into release position, for the rod lies in the path which the noses have to follow during such pivotal movement of the 115 120 125 130

jaws. It is not necessary to this condition that the noses of the two jaws extend inwardly far enough to engage one another or even to project beyond the common vertical axial 5 plane of pin 30 and way 17, nor is it necessary that faces 28 be curbed or arcuate. However, in order to insure that after the noses have become worn through use, the jaws may not be accidentally moved to release position in 10 the manners specified above, I prefer to extend noses 28 so, in securing position, they project beyond said axial plane of the pin and way. This condition may be brought about by horizontally overlapping the tips 28^a (Fig. 1) of the jaws when they are in securing position, the opposed end faces 28^b of the noses being complementarily inclined, as clearly shown in Fig. 1, to provide the overlap.

However, if body 10 be allowed to move in 20 the direction of arrow E so rod R lies nearer to or against wall 19 of way 17, as soon as the distance between the pivot point and the point on the nose which formerly engaged the rod becomes equal to or greater than the distance 25 between the pivot point and the far side of the rod in its new position, jaws 24 are capable of moving pivotally to release position, since the rod is then out of the path which said point on the nose must travel during such pivotal movement of the jaws.

Thus, when bars 13 and 37 are squeezed together in the operator's hand as he grasps them to withdraw the elevator, the body member and rod move relatively laterally so the 35 rod is nearer to way wall 19 (Fig. 3) and pivotal movement of the jaws to release position is therefore allowed. Continued squeezing together of the grips draws pivot pin 30 towards bar 13, spring 44 yielding to allow this 40 movement. Due to the crossed nature of the jaws, that is, since pin 30 is disposed intermediate the pivot point 29 and nose 26 of each jaw which point and nose are arranged at opposite sides of way 17 with the two pivot 45 points located at opposite sides of the way, this movement of pin 30 swings the jaws pivotally about points 29 into release position or until noses 26 are clear of way 17. A simultaneous or subsequent pull on the operating 50 handle moves the body member past the rod (Fig. 5) until the rod is entirely clear of the way. The operator naturally squeezes the grips together as he prepares to withdraw the elevator, so it requires no conscious effort 55 on his part to move the device elements, first, to such position that the jaws may swing to release position, and second, to move the jaws to release position.

When the operating handle is subsequently 60 released, spring 44 acts automatically to return the jaws to closed position, as will be readily understood, the elevator then being in condition for re-engagement with a rod.

The elevator may be applied to the rod 65 after first squeezing the hand grips together

to move the jaws clear of way 17 (Fig. 5) or by merely thrusting the elevator against the rod. In the latter event, the rod pressure acts against nose faces 27 to swing the jaws apart, thereby admitting the rod to the way. 70 When the rod is close to or against way wall 19, spring 44 acts automatically to project the jaws into securing position and they are subsequently held in this position against accidental release without the necessity of 75 throwing in a latch or locking mechanism of any kind.

In Fig. 8, I have shown a variational form of the invention where a single jaw 24' is substituted for the pair of jaws shown in the other figures. The jaw 24' may be fashioned and mounted in exactly the same manner as either of the jaws 24, and the operation of the device throughout will be exactly the same as that described in connection with 80 the two-jaw elevator. Parts of Fig. 8 which correspond to parts in the other figures are given corresponding primed reference numerals.

It will be understood the drawings and 90 description are to be considered merely as illustrative of and not restrictive on the broader claims appended hereto, for various changes in design, structure and arrangement may be made without departing from 95 the spirit and scope of said claims.

I claim:

1. In a sucker rod elevator, the combination of a body having a rod receiving way, a shiftable jaw on the body member and 100 adapted to secure a rod within said way, a relatively stationary hand grip on the body member, and a relatively movable hand grip pivotally connected to the jaw, said jaw being adapted to be moved to release position 105 by the squeezing together of said hand grips.

2. In a sucker rod elevator, the combination of a body having a rod receiving way, a shiftable jaw on the body member and 110 adapted to secure a rod within said way, a relatively stationary hand grip on the body member, and a relatively movable hand grip, said movable hand grip being of T-shape, the bar thereof being disposed opposite the stationary hand grip and the leg thereof being pivotally connected to the jaw, said jaw being adapted to be moved to release position 115 by the squeezing together of said hand grips.

3. In a sucker rod elevator, the combination of a body having a rod receiving way, a jaw on the body member and adapted to secure a rod within said way, said jaw having a way closing nose at one end and a pivotal connection with the body near the 125 other end, a relatively stationary hand grip on the body member, and a relatively movable hand grip operatively connected to the jaw intermediate said ends for movement therewith, said jaw being adapted to be 130

moved to release position about its pivotal connection with the body by the squeezing together of said hand grips.

4. In a sucker rod elevator, the combination of a body having a rod receiving way, a jaw on the body member and adapted to secure a rod within said way, said jaw having a way closing nose at one end and a pivotal connection with the body near the other end, said nose being disposed at one side of said way, and said pivotal connection being located at the other side of the way, a relatively stationary hand grip on the body member, and a relatively movable hand grip operatively connected to the jaw intermediate its ends, said jaw being adapted to be moved to release position about its pivotal connection with the body by the squeezing together of said hand grips.

20 5. In a sucker rod elevator, the combination of a body having a rod receiving way, a pair of pivotally connected shiftable jaws on the body member and adapted to secure a rod within said way, a relatively stationary hand grip on the body member, and a relatively movable hand grip operatively connected to the jaws for movement therewith, said jaws being adapted to be moved to release position by the squeezing together of said hand

30 grips.

6. In a sucker rod elevator, the combination of a body having a rod receiving way, a pair of pivotally connected shiftable jaws on the body member and adapted to secure a rod within said way, a relatively stationary hand grip on the body member, and a relatively movable hand grip pivotally connected to the jaws at their point of pivotal connection, said jaws being adapted to be moved

40 to release position by the squeezing together of said hand grips.

7. In a sucker rod elevator, the combination of a body having a rod receiving way, a pair of jaws on the body member and adapted to secure a rod within said way, said jaws having way closing noses at one end and pivotal connections with the body near the other end, the nose of a given jaw being disposed at one side of said way, the pivotal connection of that jaw being located at the other side of the way, said noses being in opposed relation at the way, a relatively stationary hand grip on the body member, and a relatively movable hand grip operatively connected to the jaws intermediate their ends, said jaws being adapted to be moved to release position about their pivotal connections with the body by the squeezing together of said hand grips.

60 8. In a sucker rod elevator, the combination of a body having a rod receiving way, a pair of jaws on the body member and adapted to secure a rod within said way, said jaws having way closing noses at one end and pivotal connections with the body near the other

end, the nose of a given jaw being disposed at one side of said way, the pivotal connection of that jaw being located at the other side of the way, said noses being in opposed relation at the way and having portions adapted to overlap when they are in securing position, a relatively stationary hand grip on the body member, and a relatively movable hand grip operatively connected to the jaws intermediate their ends, said jaws being adapted to be moved to release position about their pivotal connections with the body by the squeezing together of said hand grips.

9. In a sucker rod elevator, the combination of a body having a rod receiving way, a pair of pivotally connected jaws on the body member and adapted to secure a rod within said way, said jaws having way closing noses at one end and pivotal connections with the body near the other end, the nose of a given jaw being disposed at one side of said way the pivotal connection of that jaw being located at the other side of the way, said noses being in opposed relation at the way and having portions adapted to overlap when they are in securing position, a relatively stationary hand grip on the body member, and a relatively movable hand grip operatively connected to the jaws at their pivotal connection, said jaws being adapted to be moved to release position about their pivotal connections with the body by the squeezing together of said hand grips.

10. In a sucker rod elevator, the combination of a body having a rod receiving way, a jaw on the body member and adapted to secure a rod of less than given diameter within said way, said jaw having a way closing nose at one end and pivotal connection with the body near the other end, said jaw being disposed at one side of the way and adapted, when, in securing position, to project across the way at a point to allow limited relative lateral movement between the body member and secured rod, and said pivotal connection being disposed at the other side of the way, and manually operated means applied to the jaw intermediate the nose and point of pivotal connection and adapted to be actuated to shift the jaw pivotally out of securing position.

11. In a sucker rod elevator, the combination of a body having a rod receiving way, a jaw on the body member and adapted to secure a rod of less than given diameter within said way, said jaw having a way closing nose at one end and pivotal connection with the body near the other end, said jaw being disposed at one side of the way and adapted, when, in securing position, to project across the way at a point to allow limited relative lateral movement between the body member and secured rod, and said pivotal connection being disposed at the other side of the way, yieldable means adapted to hold the jaw in

- securing position, and manually operated means applied to the jaw intermediate the nose and point of pivotal connection and adapted to be actuated to shift the jaw pivotally out of securing position.
12. In a sucker rod elevator, the combination of a body member having a rod receiving way, a jaw on the body member and adapted to secure a rod of less than given diameter within said way, said jaw including a body portion having a pivotal connection at one end with the body member, a way-closing nose projecting from the other end of the body portion, said nose being adapted, when the jaw is in securing position, to project across the way at a point to allow limited relative lateral movement between the body member and secured rod, said nose being adapted to be brought into engagement with the rod at that side of the common axial plane of the rod and said point of pivotal connection which is remote from the body portion of the jaw, the jaw being so shaped that when the nose is thus engaging with the rod, the distance between the point of engagement and point of said pivotal connection is less than the distance between said point of pivotal connection and the far side of the rod as measured on said common axial plane; and the distance between said pivot point and the point of the nose which engaged the rod being not less than the second mentioned distance when the rod is moved laterally through said way for a predetermined distance from said nose.
13. In a sucker rod elevator, the combination of a body having a rod receiving way, and an oscillatory jaw on the body member and adapted to be oscillated to and from way-closing position, said jaw having a way-closing portion near one end and a pivotal connection with the body near the other end, said closing portion being disposed at one side of the way, and said pivotal connection being located at the other side of the way.
14. In a sucker rod elevator, the combination of a body having a rod receiving way, an oscillatory jaw on the body member and adapted to be oscillated to and from way-closing position, said jaw having a way-closing portion near one end and a pivotal connection with the body near the other end, said closing portion being disposed at one side of the way, and said pivotal connection being located at the other side of the way, and yieldable means adapted to hold the jaw in way-closing position.
15. In a sucker rod elevator, the combination of a body having a rod receiving way, an oscillatory jaw on the body member and adapted to be oscillated to and from way-closing position, said jaw having a way-closing portion near one end and a pivotal connection with the body near the other end, said closing portion being disposed at one side of the way, and said pivotal connection being located at the other side of the way, and yieldable means acting on the jaw intermediate the closing portion and the point of pivotal connection and adapted to hold the jaw in way-closing position.
16. In a sucker rod elevator, the combination of a body having a rod receiving way, an oscillatory jaw on the body member and adapted to be oscillated to and from way-closing position, said jaw having a way-closing portion near one end and a pivotal connection with the body near the other end, said closing portion being disposed at one side of the way, and said pivotal connection being located at the other side of the way, and means for moving the jaw about its pivotal connection.
17. In a sucker rod elevator, the combination of a body member having a rod-receiving way, a pair of jaws on the body member and each having a way-closing portion, said jaws being movable with respect to the body member in a manner to project said portions into the way from opposite sides thereof, said portions overlapping one another when in projected positions.
18. In a sucker rod elevator, the combination of a body member having a rod receiving way, a pair of jaws on the body member and adapted to secure a rod within said way, each jaw having a way-closing portion near one end and a pivotal connection with the body member near the other end, said jaws crossing one another at points intermediate their ends.
19. In a sucker rod elevator, the combination of a body member having a rod receiving way, a jaw, a pivotal connection between the body member and jaw whereby the jaw is movable to and from way-closing position; said connection being characterized as gear-tooth engagement between the body member and jaw, and means for maintaining such engagement.

In witness that I claim the foregoing I have hereunto subscribed my name this 14th day of January 1926.

EDWARD E. STEVENSON.
